UNITED STATES PATENT OFFICE.

ABRAHAM LACKEY, OF RIALTO, CALIFORNIA.

MIXING MACHINE.

1,408,609.

Specification of Letters Patent.

Patented Mar. 7, 1922.

Application filed August 29, 1921. Serial No. 496,313.

To all whom it may concern:

Be it known that I, ABRAHAM LACKEY, a citizen of the United States, residing at Rialto, in the county of San Bernardino and State of California, have invented certain new and useful Improvements in Mixing Machines, of which the following is a specification, reference being had to the accompanying drawings.

10 This invention relates to mixing machines and more particularly to machines for mixing finely divided or comminuted material such as fertilizers, washing powders or the like.

15 One of the principal objects of the invention is to provide a simple, inexpensive and efficient machine of this character which will thoroughly mix the ingredients in fertilizers, washing powders or the like.

20 A further object of the invention is to provide a machine of this character embodying a screw conveyor so arranged with respect to other parts of the machine that the material will be mixed and remixed until a 25 desired comingling of the elements is attained.

Another object of the invention is the provision of novel means for discharging the mixed material from the mixer when the 30 ingredients have been thoroughly com- gled.

Further objects of the invention will appear as the following specific description is read in connection with the accompanying 35 drawings which form a part of this application and in which:

Figure 1 is a side elevation;

Figure 2 is a vertical sectional view;

Figure 3 is a top plan view;

40 Figure 4 is a detail elevation with parts broken away, showing the position of the discharge chute used when the elements of the material being mixed are thoroughly comingled.

45 Figure 5 is a fragmentary plan view of the chute.

Referring more particularly to the drawing, 1 represents a cylindrical casing constructed of any suitable material and of any 50 suitable size which is supported upon a plurality of legs 2, and is provided with a frusto-conical bottom 3. Mounted within the casing 1 is a cylinder 4 which rests upon the bottom 3, as shown in Figure 2, and 55 which terminates short of the top of the

casing so that material elevated therein will overflow into the casing as will be presently understood. Mounted within the cylinder 4 and having its lower end journaled in a step 60 bearing 5 is a shaft 6 carrying a screw conveyor 7 which fits the cylinder as shown. The upper end of the shaft is journaled in a bearing 8 formed in a cross bar or spider 9 extending across the open upper end of the 65 casing 1.

Mounted in suitable bearings 10 and 11 supported respectively upon the casing and cross bar 9 is a driving shaft 12 having upon its inner end a beveled gear 13 arranged to 70 mesh with a corresponding gear 14 upon the upper end of the shaft 6. The shaft 12 is provided with a belt pulley 15 which is connected to a source of power, not shown, and which is adapted to drive the shaft 12 75 so as to produce a continuous movement of the screw conveyor 7 in one direction, i. e., a direction to lift the material fed into the cylinder, as will be now described. The lower end of the cylinder 4, immediately 80 adjacent its contact with the bottom 3, is provided with a plurality of openings 16 through which the material contained in the casing 1 passes into the cylinder 4 and is picked up by the screw conveyor 7. 85

In the operation of the device, the casing 1 is filled or partially filled with the respective ingredients to be mixed and the shaft 12 rotated so as to drive the screw conveyor in such a direction as will elevate the material 90 passing from the casing 1 into the cylinder 4 through the apertures or openings 16. The material entering the openings 16 is picked up by the conveyor and carried to the top of the cylinder 4 where it overflows into the 95 casing again. This continued operation insures a thorough comingling of the ingredients which go to make up the combination, such as fertilizers, washing powders, or the like. 100

Surrounding the upper end of the cylinder and frictionally maintained in fixed position thereon is a ring 17 having an up-standing guard 18 of semicircular outline formed integrally therewith. The casing 1 105 is provided with a door 19 through which a chute or trough 20 is adapted to pass. This chute or trough, as shown, is substantially semicircular in cross section and is provided at its inner end with a notch 21 forming 110 straddling arms or legs 22 arranged to em-

brace the ring and guard 17 and 18, as shown in Figure 4.

Normally when mixing material in the casing, the chute or trough 20 is removed and 5 the ring 17 with its guard 18 is lowered below the top edge of the cylinder 4 so as to permit the overflow of the material being mixed in all directions from the upper end 10 of the cylinder. When the material has been thoroughly mixed, the ring 17 is slid up on the cylinder 4 until the guard 18 projects a considerable distance above the same and the member 19 opened and the chute or trough 20 inserted so that the arms 22 straddle the ring 15 and guard, as shown. The material then discharged from the cylinder 4 cannot escape to either side of the cylinder, but is directed by the guard 18 into the chute 20 from whence it may be discharged into any suitable receptacle, or may be fed into cartons or other 20 containers for shipment.

What I claim is:

1. In a mixing machine, a casing, a cylinder mounted in the casing and arranged to receive material from the casing adjacent its bottom, means in the cylinder for elevating 25 the material received and discharging it at

the top of the casing into the cylinder, a door in the casing, a chute passing through the door, and a guard slidably mounted upon the cylinder and associated with the chute for directing the material discharged from the cylinder into the chute. 30

2. In a mixing machine including a casing, an upright cylinder mounted in the casing and communicating with the latter at its bottom whereby to receive material from the casing, means operating within the cylinder for elevating the material received and discharging it at the top of the cylinder, and a door in the casing; means for conducting material discharged at the top of the cylinder to the outside of the casing comprising a collar slidably adjustably mounted at the upper end of the cylinder and formed with a 40 cut away portion, and a chute insertible through said opening and having a slotted end engageable about said collar with the inner end of the slot disposed against the collar immediately below the cut away portion 45 of the latter.

In testimony whereof I hereunto affix my signature.

ABRAHAM LACKEY.
